Inventor

Abel Greenleaf

UNITED STATES PATENT OFFICE.

A. GREENLEAF, OF KINGSTON, PENNSYLVANIA.

IMPACT WATER-WHEEL.

Specification of Letters Patent No. 11,296, dated July 11, 1854.

To all whom it may concern:

Be it known that I, ABEL GREENLEAF, of 5
Kingston, in the county of Luzerne and
State of Pennsylvania, have invented cer-
tain Improvements in Gravity and Percus-
sion Water-Wheels; and I do hereby declare
that the following is a full, clear, and exact
description of the construction and opera-
tion thereof, reference being had to the ac-
companying drawings, making part of this
specification, in which—

Figure 1 represents an end view, and Fig.
2 a top view of the wheel.

The letters refer to the same parts in the
different figures.

The nature of my invention consists in
attaching to and combining in a laterally
discharging water wheel a series of vertical
and horizontal flanges or buckets, construct-
20 ed and arranged as hereinafter described,
and possessing advantages over other wheels
in which buckets constructed on similar
principles are used, but separately and un-
combined.

25 I construct a wheel of cast iron or other
suitable material and place it on a shaft (A)
with suitable bearings in a scroll case or
water chutes (not shown) made in any of
the usual forms. Upon the hub D I place
30 vertical buckets B (by which I mean buckets
which are perpendicular to the axis of the
wheel in any of its sections in the line of
said axis) approaching in a spiral form from
the end of the wheel at *a* toward the center
35 of its periphery, and stopping at *b* where
also the horizontal buckets C (by which I
mean buckets which are parallel to the axis
of the wheel in any of its sections in the line
of said axis) terminate, which gradually rise
40 from the point *e* in a convex curve to the

periphery of the wheel. I sometimes, in or-
der to save expense in construction, when a
high velocity is not required, leave out the
portion of the wheel contained between the
lines *d*, *e*, and *f* and above the level of the 45
horizontal buckets, thus throwing two
buckets into one. The space between the
edges of the vertical buckets and the ends of
the wheels are covered by a rim (E).

The water being admitted into the scroll 50
case or chute presses by its weight and mo-
mentum against the surfaces of the vertical
and horizontal buckets and escapes at the
apertures F at the ends of the wheel.

The material advantages to be derived by 55
using the horizontal and vertical buckets
combined as before described are in the first
place the prevention of the action of the
portion of the water which would otherwise
act upon the portions of the vertical buckets 60
between the dotted lines in Fig. 1 and the
hub D and causing it to give out its effective
force nearly at the periphery of the wheel,
making a great gain in leverage; secondly,
it has a tendency to give a more steady ac- 65
tion and uniform motion to the wheel.

What I claim as my invention and desire
to secure by Letters Patent is—

The combination of the horizontal buckets 70
C with the vertical buckets B substantially
in the manner described and for the pur-
poses specified.

In testimony whereof I have hereunto
signed my name this 20th day of April,
1854.

ABEL GREENLEAF.
